Attorneys.

UNITED STATES PATENT OFFICE.

JACOB PETRY, OF PITTSBURGH, PENNSYLVANIA.

DENTURE.

Application filed April 14, 1924. Serial No. 706,603.

My invention relates to dentures and particularly to the means whereby said dentures are maintained in the mouth of the wearer.

5 My invention has for one of its objects the provision of a denture of such form that the suction device may be readily placed therein in proper alignment.

Another object of my invention is to simplify and improve generally the manufacture of devices of the character above referred to.

One form which my invention may take is shown in the accompanying drawing 15 wherein Fig. 1 is a perspective view of a completed denture, with the suction device in position; Fig. 2 is a sectional view, on an enlarged scale taken on the line 2—2 of Fig. 1, previous to the insertion of the suction member; Fig. 3 is a view similar to that of Fig. 2 with the suction member in position; Fig. 4 is a view of the suction device previous to insertion in the denture, and Fig. 20 5 is a view of a portion of a metallic member for forming a recess in the denture.

The denture or dental plate 5 as shown in the drawing, is intended to fit upon the lower jaw being shown in the drawing in inverted position, for greater clearness of 30 illustration. This denture 5 may be made somewhat after the usual manner but instead of being provided with an arcuate recess whose bottom surface is disposed in substantially a horizontal plane in accordance 35 with the usual practice, I provide a recess 6 for the reception of a suction plate 7 composed mainly of rubber or like material and having the usual suction cups 8 for engagement with the gums of the wearer. The 40 suction plates 7 with the cups attached thereto, are usually made in strips which are cut to the desired length and then inserted into the dentures, but in bending the plate 7 as indicated in dotted lines in Fig. 45 50 to permit of its insertion into the denture, the front portion thereof tends to tip backwardly, thus inclining the front or intermediate suction cups 8 to such an extent that they will not properly seat against the gums.

In order to overcome this difficulty I

depress the forward extremity of the recess 6 slightly as indicated in Fig. 2. It will be observed that the downward inclination of the bottom of the recess 6 tends to tip those 55 cups, which are adjacent to that point, forwardly, thus compensating for or counteracting the tendency of the cups to be tipped backwardly when the plate 7 is inserted in the denture.

60 The denture 5 is of molded material of any suitable character and the recess is formed therein by means of a pattern consisting preferably of a metallic member 9 having the desired arcuate form and which 65 is withdrawn after formation of the depression or groove in the denture. The undercut portions of the recess 6 are then cut or milled out for the reception of the edges of the suction plate 7, the suction plate 7 being 70 cemented in position in the recess, somewhat after the manner set forth in my Patent No. 1,463,968 issued August 7, 1923.

In order to give a clearer understanding 75 of how the recess 6 is formed, I have shown in Figure 5 substantially one-half of the metallic member 9 about which the denture is molded in forming the recess. This member 9 is of substantially uniform thickness along its entire inner edge. At its periphery or outer edge the thickness of the member 9 commences to gradually increase at about the point *a* and reaches its maximum thickness at the foremost point *b* where it is desired that the groove 6 shall have its 80 greatest depth.

85 Continuing from the point *b*, the thickness of said outer edge of the member 9 gradually decreases in substantially the same degree as from *b* to *a*, one-half of the 90 parts 9 being omitted for the sake of clearness. It will thus be seen that the vertical height of the rear wall of the groove is substantially uniform from end to end and that the vertical height of the outermost wall of 95 the groove increases towards the front of the recess but is of substantially the same height adjacent to the rear ends of the recess 6 as the inner wall thereof.

100 While I have described a manner in which the recess may be formed it will be apparent that I do not limit myself in this

case to the means thus described, but my invention includes all such modifications as may come within the terms of the accompanying claims.

5 5. What I claim is:

1. A denture provided with a substantially horizontal arcuate recess having a flat bottom whose outer edge, intermediate the

ends of the recess, is inclined downwardly.

2. A denture provided with a curved recess having a substantially flat bottom whose forward edge, intermediate the ends of the recess, is inclined.

In testimony whereof I, the said JACOB PETRY, have hereunto set my hand.

JACOB PETRY.
